UNITED STATES PATENT OFFICE.

ARTHUR MCLEAN, OF SEATTLE, WASHINGTON.

WRENCH.

1,150,687.

Specification of Letters Patent. Patented Aug. 17, 1915.

Application filed April 22, 1915. Serial No. 22,986.

To all whom it may concern:

Be it known that I, ARTHUR MCLEAN, a citizen of the United States, and a resident of Seattle, in the county of King and State of Washington, have invented a new and useful Improvement in Wrenches, of which the following is a specification.

My invention is an improvement in wrenches, and has for its object to provide a tool of the character specified especially adapted for placing or removing threaded flanges on pipes wherein the wrench is so arranged that it may be rigidly connected to flanges of various sizes, and wherein mechanism is provided in connection with the wrench for turning the wrench and the flange in either direction.

In the drawings:—Figure 1 is a top plan view of the improved wrench, Fig. 2 is a transverse vertical section through the center of the wrench, Fig. 3 is a side view with parts broken away, Figs. 4 and 5 are detail sectional views through the ratchet rings, showing the parts in different positions, and Fig. 6 is a perspective view of one of the connecting bolts.

The present embodiment of the invention comprises a pair of concentric ratchet rings 1 and 2, the ring 2 being arranged within the ring 1, and the rings are of such relative size that there will be an annular space between the rings. The inner ring 2 has a central hub 3, and pairs of radial bars 4 and 5 extend radially from the hub to the inner surface of the ring. The bars 4 are similar to the bars 5, and the said bars 4 and 5 may be considered as continuous and arranged diametrically of the ring.

Braces 6 are arranged between the outer faces of the bars of the pairs and the ring, the braces 6 at each side of the bars 4 and 5 being approximately parallel. The braces 6 may be considered as continuous parallel braces and reinforcing bars arranged on opposite sides of the rings. The ring 1 is provided on its upper edge with a series of ratchet teeth 7, and the ring 2 is provided with a similar series 8, the teeth of the ring 2 however, facing in the opposite direction to the teeth of the ring 1.

It will be noticed from an inspection of Fig. 2 that the ring 2 is of greater depth or thickness than the ring 1, and when the lower edges of the rings are arranged flush with each other, the teeth 8 of the ring 2 will extend above the teeth 7 of the ring 1.

The ring 2 is provided on its periphery with a rib 9, to be later described, which bears against the inner face of the ring 1, and a set screw 10 is threaded through the ring 1, 60 the said set screw engaging the periphery of the ring 2.

The hub 3 is recessed on its under side as indicated at 11, and a bolt 12 is passed through the hub at the center thereof, the 65 said bolt being also at the center of the recess, and the recess is axial with respect to the hub and the ring. That portion of the bolt 12 adjacent to the head is polygonal as shown at 13, and the end of the bolt is 7, threaded.

A follower 14 is arranged on the bolt, the interior of the follower being shaped to fit the exterior of the bolt. The follower is of such size as will fit loosely in the recess 11, 75 extending however, from near the inner end of the recess to the head of the bolt 12. It will be noted that internally the follower is shaped to fit the polygonal portion, and a coil spring 17 is arranged within the recess 80 outside of the follower, the spring bearing at its inner ends against the bottom of the recess and at its outer end against the head 15 of the follower or sleeve 14.

The bolt is passed from within upward, 85 that is, the head of the bolt is at the lower end of the follower and the upper end of the bolt extends above the hub, passing through the pawl arm 19 to be later described, and above the arm the bolt is engaged by a nut 90 18 to hold the parts in place.

The pawl arm 19 is mounted on the bolt, the said arm being above the rings, and the arm has a central hub 20, which engages the bolt. The arm extends diametrically of the ring, and washers are arranged between the nut 18 and the pawl arm and between the head of the bolt and the lower end of the sleeve 14. The pawl arm is provided with pawls 21 for engaging the teeth 7 of 100 the ring 1 and with pawls 22 for engaging the teeth 8 of the ring 2, and the pawls 22 are oppositely arranged with respect to the pawls 21. The pawls 21 and 22 are so arranged that when the pawl arm is oscillated in one direction the ring 1 will be moved angularly, while when the arm is oscillated in the opposite direction the ring 2 will be moved angularly.

The bars 4 and 5 form guide ways extending radially of the wrench, and a bolt is arranged in each guide way. Each bolt

comprises a polygonal portion 23 fitting between the bars 4 or 5, as the case may be, a head 24 rigid with the bolt and extending at opposite sides to the outer face of the bars 4-5, and a threaded portion 26 on the opposite side of the polygonal portion from the head.

The polygonal portion is of such length that the lower end thereof will be flush with the lower side edges of the bars 4 or 5, and a nut 27 is threaded on to each bolt, a washer 28 being arranged on the inner side of the nut. The upper edges of the bars 4 and 5 have ratchet teeth as shown, and it will be noticed that the teeth of the bars 4 face outwardly from the bolt 12, as do also the teeth of the bars 5, that is, the teeth of the bars 4 face in the opposite direction to the teeth of the bars 5. The under faces of the heads 24 of the bolts 23-24-26 are also provided with teeth for co-operating with the teeth of the bars.

It will be noticed that the teeth of the bars of each pair 4 and 5 are inclined in opposite directions. The teeth of each bar incline outwardly, the inner end of the tooth being nearer the center of the wrench than the outer end, and the teeth of the heads 24 of the bolts are similarly arranged, that is, the said teeth are shaped to fit the teeth of the bars. The heads 24 of the bolts are below the level of the teeth of the rings, so that the said heads do not interfere with the movement of the arms 19. One end of the arm 19 is provided with a socket 25, and the socket is designed to receive an operating handle 29. This handle has a radial pin 30, and the socket has a bayonet slot 31 for engagement by the pin to lock the operating handle in the socket.

The improved wrench is as before stated, especially designed for turning flanges on to pipes. As shown in Fig. 2 the pipe 32 has its upper end threaded as indicated at 33. The flange 34 is of angular material, and is internally threaded to engage the thread of the pipe.

In use, the bolts 23-24-26 are inserted through openings 35 in the flange, and the nuts 27 are then turned into place to clamp the wrench to the flange. The bolts 23-24-26 are adjustable toward and from each other, to provide for flanges and pipe of different size, and the toothed engagement of the heads of the bolts with the upper edges of the bars prevents displacement of the bolts during the placing of the wrench or during the operation of the same. The bolts being square in the guideways, that is, being shaped to fit the guide ways, are held from turning while the nuts 27 are screwed into place.

In order to permit the teeth of either ring to be engaged by the pawls pertaining thereto, mechanism is provided for permitting

the rings to be shifted axially with respect to each other. It will be noted from an inspection of Fig. 3 that the outer surface or periphery of the ring 2 is recessed. Each of the recesses comprises a portion 36, extending from the bottom edge of the ring upwardly to about two-thirds the height of the ring, and parallel extensions 37 and 38 lead off from the portion 36 of each recess in the same direction. Each recess 36 extends from the bottom of the ring through the rib 9, as shown in Fig. 3, and at each of the said recesses 36-37-38, the ring 1 is provided with an inwardly extending lug or tongue 39 for engaging the recesses.

It will be understood that as a rule, three recesses 36-37-38 are provided, and three tongues 39, the tongues and the recesses being spaced apart at equal distances with respect to each other. When the ring 2 is turned angularly with respect to the ring 1 to bring the lugs or tongues 39 into register with the lower end of the recesses 36, it will be obvious that the ring 2 may be moved downwardly with respect to the ring 1. When the tongues are in engagement with the recesses 37 the teeth 8 of the ring 2 are at a higher level than the teeth 7 of the ring 1. When however, the tongues 39 are in engagement with the recesses 38, the ring 1 has its teeth at a higher level than those of the ring 2.

The set screws 10 by their engagement with the ribs 9 limit the movement of the rings with respect to each other axially in one direction. When the wrench has been placed on the pipe as above described, with the rings 1 and 2 adjusted properly, so that the pawls of the ring which it is desired to turn may engage with the teeth of the ring, the wrench is ready for operation. The outer ring 1 may be adjusted with respect to the ring 2 after the ring 2 has been secured to the flange, if desired, as it is only necessary to loosen the set screws 10 and turn the ring 1 until the tongues 39 register with the recesses 36. When it is desired to turn a flange on to the pipe, the ring 2 is so placed with respect to the ring 1 that the teeth 8 are accessible to the pawls 22. The flange is now placed in position on the pipe, it being understood that the set screws 10 have been retightened and that the bolts 23-24-26 have been connected to the flange. The pawl arm is now vibrated on the bolt 12 to drive the ring 2 forwardly, and since this ring is rigidly secured to the flange the flange will be turned on to the pipe. The pawl arm may be rotated or vibrated, moving the ring 2 forwardly on its forward stroke, while the pawls 22 slip idly over the teeth on the reverse stroke. The yielding arrangement of the bolt 12 permits the pawl arm to yield upwardly during the reverse movement. When it is desired to re-

move a flange the ring 1 is raised with respect to the ring 2, by loosening the set screws 10 as above mentioned, and the tongues 39 are engaged with the portions 38 of the recesses 36.

The set screws 10 are tightened, and by means of the bolts 24—25—26 the wrench is rigidly secured to the flange, which is in place on the pipe. Now the pawl arm is vibrated to move the ring 1 rearwardly. On the reverse movement of the pawl arm the pawls 21 slip idly over the teeth but on the forward movement of the said arms the pawls engage the teeth, reversing the direction of turning of the flange and finally loosening the same. Preferably the ring 1 is provided with small depressions or the like in its under side edge for engagement by the fingers to move the ring axially with respect to the ring 2.

It will be noted that the ring 2 fits snugly within the ring 1, in order that each ring will reinforce the other, and will thus prevent springing of the rings, enabling the wrench to be made lighter in weight. The only purpose of the set screw 10 is to cause sufficient friction to hold the working ring on the back stroke of the pawl arm, thus preventing any lost motion between the rings. The set screw also prevents disengagement of the rings when they are not in use, holding them together during transportation and the like.

When it is desired to shift the rings with respect to each other the set screw must be loosened and the bolt must also be loosened by turning the nut 18. For this reason the nut is at the top, or outside of the pipe to permit free access thereto.

It will be noted that in practice the socket 25 is turned just opposite to what it is shown in Fig. 1, that is, the slot 31 is on the under side of the socket as is also the pin 31 to prevent the pin working out of the socket.

I claim:—

1. A wrench comprising a pair of concentric ratchet rings, said rings having ratchet teeth on their upper edges and the teeth of one ring facing in the opposite direction to those of the other ring, the inner ring having a hub and having oppositely arranged alined radial guide ways, bolts movable in the guide ways for rigidly connecting the rings to the flange of a pipe, the heads of the bolts extending beyond the guide ways at each side of the bolt and the said heads and upper edges of the guide ways having interengaging teeth for preventing movement of the bolts in the guide ways, a pawl arm extending diametrically of the rings and having a pair of pawls for the teeth of each ring and arranged to engage the teeth of the ring at diametrically opposite points, a yielding mounting for the arm for permitting the arm to move upward, and means in

connection with the rings for permitting them to be moved axially with respect to each other to bring either set of teeth into operative position, and to hold the rings in adjusted position, said means comprising inwardly extending tongues on the outer ring, and recesses at the tongues on the inner ring, each recess extending from the lower edge of the ring to near the top thereof and having a pair of parallel, lateral extensions for engagement by the adjacent tongue to hold either ring with its teeth at a higher level than those of the other ring, and means for rigidly connecting the rings to prevent angular movement with respect to each other. 70 75 80

2. A wrench comprising a pair of concentric ratchet rings, said rings having ratchet teeth on their upper edges and the teeth of one ring facing in the opposite direction to those of the other ring, the inner ring having a hub and having oppositely arranged alined radial guide ways, bolts movable in the guide ways for rigidly connecting the rings to the flange of a pipe, the heads of the bolts extending beyond the 85 guide ways at each side of the bolt and the said head and upper edges of the guide ways having interengaging teeth for preventing movement of the bolts radially of the guide ways, a pawl arm extending diametrically 90 of the rings and having a pair of pawls for the teeth of each ring and arranged to engage the teeth of the ring at diametrically opposite points, a yielding mounting for the 95 arm for permitting the arm to move upward, 100 and means in connection with the rings for permitting them to be moved axially with respect to each other to bring either set of teeth into operative position, and to hold the rings in adjusted position. 105

3. A wrench, comprising a pair of concentric ratchet rings, said rings having ratchet teeth on their upper edges and the teeth of one ring facing in the opposite direction to those of the other ring, the inner ring having a hub and having oppositely arranged alined radial guide ways, bolts movable in the guide ways for rigidly connecting the rings to the flange of a pipe, a pawl arm extending diametrically 115 of the rings and having a pair of pawls for the teeth of each ring and arranged to engage the teeth of the ring at diametrically opposite points, a yielding mounting for the arm for permitting the arm to move upward, and means in connection with the ring for permitting them to be moved axially with respect to each other to bring either set of teeth into operative position, and to hold the rings in adjusted position, said means comprising a 120 series of inwardly extending radial tongues on the outer ring, and recesses on the inner ring for engagement by the tongues, each recess extending from the lower edge of the ring to near the top thereof and having a 125 130

pair of lateral approximately parallel extensions for engagement by the adjacent tongue to hold the rings in adjusted position.

4. A wrench comprising a pair of concentric ratchet rings, said rings having ratchet teeth on their upper edges and the teeth of one ring facing in the opposite direction to those of the other ring, the inner ring having a hub and having oppositely arranged aligned radial guide ways, bolts movable in the guide ways for rigidly connecting the rings to the flange of a pipe, a pawl arm extending diametrically of the rings and having a pair of pawls for the teeth of each ring and arranged to engage the teeth of the ring at diametrically opposite points, a yielding mounting for the arm for permitting the arm to move upward, and means in connection with the rings for permitting them to be moved axially with respect to each other to bring either set of teeth into operative position, and to hold the rings in adjusted position.

5. A wrench comprising a pair of concentric rings, each ring having ratchet teeth on its upper edge and the teeth facing in opposite directions, the inner ring having a hub, a pawl arm extending diametrically of the rings and pivotally connected to the hub to yield upward with respect thereto, said pawl arms having a pair of pawls for engaging the teeth of each ring, and the members of each pair being at diametrically opposite points on the ring, means for permitting the rings to be moved axially with respect to each other to bring the teeth of either ring out of engaging position with its pawls and for holding the rings rigidly in adjusted position, and means for rigidly securing the inner ring to a flange, said means comprising radial guide ways extending from the hub in opposite directions and in alignment, a bolt engaging each guide way, each bolt having a polygonal portion at the guide way for preventing rotation of the bolt, and the lower end of the bolt being adapted to pass through an opening in the flange, the head of each bolt extending above the side edges of the guide way on each side of the bolt, each head and the upper edges of the guide ways having interengaging means for preventing movement of the bolt in the guide way.

6. A wrench comprising a pair of concentric rings, each ring having ratchet teeth

on its upper edge and the teeth facing in opposite directions, the inner ring having a hub, a pawl arm extending diametrically of the rings and pivotally connected to the hub to yield upward with respect thereto, said pawl arms having a pair of pawls for engaging the teeth of each ring, and the members of each pair being at diametrical opposite points on the ring, means for permitting the rings to be moved axially with respect to each other to bring the teeth of either ring out of engaging position with its pawls and for holding the rings rigidly in adjusted position, and means for rigidly securing the inner rings to a flange.

7. A wrench comprising a pair of concentric ratchet rings, the rings having teeth on their upper edges and the teeth of one ring facing in the opposite direction to the teeth of the other ring, means in connection with the rings for securing them to the flange of a pipe, a common pawl arm journaled concentric with the rings intermediate the ends of the arm and having pawls for engaging the rings, and means in connection with the rings for permitting them to be moved axially with respect to each other to bring the teeth of either ring into operative position and for holding the said rings in adjusted position.

8. A wrench comprising a pair of concentric ratchet rings, the teeth of the rings facing in opposite directions and being on the upper edges thereof, means in connection with the rings for securing them to the flange of a pipe, a pawl arm journaled concentric with the rings and having a pawl for engaging each ring, and means in connection with the rings for permitting them to be moved axially with respect to each other to bring the teeth of either ring into operative position.

9. A wrench comprising a pair of concentric ratchet rings, the teeth of the rings facing in opposite directions and being on the upper edges thereof, means in connection with the rings for securing them to the flange of a pipe, and a pawl arm journaled concentric with the rings and having a pawl for engaging each ring.
